SIPHON

Toivo C. Pasanen, Franklin Mine, Mich.

Application August 19, 1953, Serial No. 375,260

2 Claims. (Cl. 137—150)

1

The present invention relates to a siphon construction and it consists in the combinations, constructions and arrangements of parts herein described and claimed.

Generally there is provided a siphon construction consisting of a flexible tube upon one end of which is slidably mounted by means of an airtight bushing a rubber bulb, the bushing being formed in the inner end of the bulb and the outer end of the bulb being provided with a novel valve. The device is such that a quick squeeze of the bulb will create a partial vacuum in the tube to start a flow of fluid therethrough and the valve may be held open by extending the tube therethrough during the operation of the device.

It is accordingly an object of the invention to provide a novel siphon construction.

Another object of the invention is to provide, in a device of the character set forth, novel means for starting a siphoning action in a tube forming a part of the invention.

A further object of the invention is to provide, in a device of the character set forth, a novel valve forming a part of the invention.

Another object of the invention is to provide a device of the character set forth which is simple in construction, inexpensive to manufacture and yet effective and efficient in use.

Other and further objects of the invention will become apparent from a reading of the following specification taken in conjunction with the drawing, in which:

The figure is an exploded perspective view of an embodiment of the invention.

Referring more particularly to the drawing, there is shown therein an elongated tube 10 having an inlet end 11 and an outlet end 12. A collapsible bulb 13 is provided as a part of the invention and is provided at one end with an airtight bushing 14 through which the outlet or discharge end portion of the tube 10 is adapted to slidably extend. The other end of the bulb 13 is provided with a tubular portion 15 to the free end of which is pivotally connected, as indicated at 16, a circular metal flat valve 17 having a coating 18 of rubber or the like upon the inner face thereof. A thumb tab 19 is formed integrally

with the valve 17. The tube 10 is provided with an outstanding collar 20 in that portion thereof which extends through the bulb 13.

In operation, it will be apparent that by inserting the inlet end 11 of the tube 10 into liquid to be siphoned and thereafter closing the valve 17 by means of the tabs 19 while the outlet end 12 of the tube is within the bulb 13 and thereafter squeezing the bulb 13, that air will be forced from the tube 10 through the inlet opening 11 whereupon, when the bulb 13 resumes its natural shape, liquid will be drawn into the tube 10 and thereafter flow by conventional siphoning action through the discharge opening 12. During this time the bulb 13 may be moved along the tube 10 so that the discharge end 12 projects through the cylindrical portion 15 to maintain the valve 17 in opened condition thus permitting a clean flow of fluid therethrough.

While but one form of the invention has been shown and described herein, it will be readily apparent to those skilled in the art that many minor modifications may be made without departing from the spirit of the invention or the scope of the appended claims.

What is claimed is:

1. A device of the character described comprising an elongated tube having an inlet opening at one end thereof and an outlet opening at the other end thereof, a collapsible bulb having a watertight bushing at one end thereof, slidably receiving therethrough the outlet end portion of said tube, a cylindrical portion at the other end of said bulb and adapted to receive the outlet end of said tube therethrough, and a flap valve pivotally connected to the free end of said cylindrical portion.

2. A device as defined in claim 1 wherein said valve is provided with a thumb tab for operating the same, and wherein said tube is provided with a collar in that portion thereof lying within said bulb.
